CLAIM

(57) The ornamental design for a printer, as shown and described herein.

DESCRIPTION

FIG. 1 is a front, top, and left side perspective view of a printer;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof, which is a mirror image of a right side elevational view thereof; and,

FIG. 7 is a front, top, and left side perspective view of a printer.

Those portions of the Figures shown in broken lines are included for illustrative purposes only and form no part of the claimed design.
